WASHING MACHINE DRIVE

Job Hutchinson, Great Neck, N. Y.

Application September 23, 1947, Serial No. 775,576

8 Claims. (Cl. 74—70)

1

This invention relates to new and useful improvements in washing devices and has particular reference to washers which can be easily and quickly placed into and removed from tubs or basins as a unit.

It is an object of this invention to provide a simple, compact, washing device which can be placed into a tub and connected to a source of power to effectively agitate the water in which it is placed while at the same time being entirely immune from said liquid while in the tub.

Further, it is an object to provide a simple rugged device composed of component units which can be assembled with ease and with equal ease taken apart for replacement, inspection, and repair.

A further object is to provide a device wherein in the various units forming the complete unit can be manufactured separately and then quickly assembled so as to reduce cost and labor involved in the manufacture of the device and so that when one unit wears out it can be replaced without the customer having to buy a complete new unit.

Further and more specific objects, features and advantages will more clearly appear from a consideration of the detailed specification herein-after set forth especially when taken in connection with the accompanying drawings which illustrate several forms which the invention may assume and which forms part of the specification.

In brief and general terms the invention concerns the provision of a casing having an oscillatable cap on which are removably disposed paddles preferably extending down along the side of the casing. Within the casing is a motor and gear worm unit also separately removable as a unit therefrom and including drive elements such as disks with eccentric pins thereon preferably driven in opposite directions. On the cap is disposed a driven element which may be in the form of a dependent element or flange engaged by the pins so as to be oscillated back and forth to oscillate the cap and thus the paddles. In one form the driven element may include separate pivoted dependent arms backed by a spring to engage the pins and increase the quietness of the operation.

In more particularity the cap, the paddles and the attached driven element on the cap form a unit which can be easily lifted off the casing as a whole and the paddles as easily removed from the cap. The cap is preferably disposed for

2

oscillation on the casing in a liquid-tight manner so that no liquid can get into the casing.

Because of these general features the device is simple, rugged, relatively inexpensive to produce and low in cost of operation.

Further features of the invention will appear from the following specification and claims.

A present preferred form which the invention may assume is illustrated in the drawings, of

10 which—

Fig. 1 is a vertical section taken on the line 1—1 of Fig. 2;

Fig. 2 is a horizontal section taken on the line 2—2 of Fig. 1;

15 Fig. 3 is a vertical transverse section taken on the line 3—3 of Fig. 2;

Fig. 4 is a detailed elevation of a modified form of paddles;

20 Fig. 5 is an elevation of a modified form of driven means between the drive pins and the paddles;

Fig. 6 is a horizontal section thereof taken on the line 6—6 of Fig. 5;

25 Fig. 7 is a partial vertical section through a modified form of the invention showing an attached controlling overflow pipe.

Fig. 8 is a cross sectional view of a unit installation where the invention is permanently installed; and

30 Fig. 9 is a sectional view taken on the line 9—9 of Fig. 8.

Referring now merely to the preferred form of the invention shown in the drawings, it is seen that there is provided a casing 10, preferably cylindrical in section and of considerable depth, closed at the bottom and open at the top. To this casing is integrally connected a much larger base 11. The outer walls of the casing 10 and the upper face of the base plate 11 are provided with reinforcing ribs 12 in order to give the same effect to the clothes as would be given by a washboard.

The casing 10 is provided with an oscillatable cap 13 having a peripheral flange 14 fitting in a liquid-tight manner around the upper edge of the casing. To the top of this cap 13 are removably fastened a pair of paddles 15 by means of bolts 16. These paddles have apertured portions 17 extending down along the sides of the casing 10. In the modified form of paddle shown in Fig. 4, the paddles have an extension 18 which may be supported therefrom on extension rods 19 seated in suitable bores in the main portion of the paddle 15.

55 Connected to the underside of the cap 13 by

means of bolts 20 (see Fig. 3) is a driven plate or element 21 having a chord-like dependent integral flange 22. This is adapted to be engaged by eccentric pins 23 mounted on disks 24 supported on disk shafts 25. These disks are disposed above a frame formed by connected spaced plates 26 and 27 and between these plates the disk shafts 25 are connected to worm gears 28 driven by a common worm 29 on a shaft 30 carrying a belt pulley 31 connected by a belt 32 to a similar pulley 33 on a shaft 34 of a motor 35. This motor is mounted in any suitable manner on a base plate 36 having on its under side a groove 37 adapted to receive a rib 38 formed on the floor of the casing 10 and diametrically disposed on said floor. The frame plates 26 and 27 are supported from the plate 36 by means of legs 39. It will be clear then that the disks, their operating gears, the motor and the connections between the motor and the gear train are one unit supported within the casing and separable therefrom merely by being lifted therefrom as desired. It is also clear that the cap and the paddles are separable and that the cap and/or the paddles can be removed as a unit from the casing since the driven flange 22 is not positively connected to the driving pins. It is shown that the disks drive the pins in opposite directions.

In the modified form shown in Fig. 6, the flange 22 is cut away on opposite sides of its central hub 40 and in these cut-away portions are pivotally disposed arms 41 to be engaged by the pins 23. These arms are backed resiliently by a spring plate 42 fastened to the hub 40 and are intended to resist the thrust of the pins on the arms. This construction will permit a more quiet operation than the one shown in Fig. 1. The arms 41 are dependent essentially from the cap through the intermediary of the flange 22 in which they are disposed.

In order to bring electric power into the casing it is accomplished in the following manner:

The motor wires 43 are passed through a hole in a boss element 44 disposed centrally on top of the frame plate into which is screwed one threaded end 44 of a hollow bushing 45 which passes through a central hole in the flange plate 21. The opposite threaded end 46 of said bushing is screwed into a recess in the bottom of a cup-shaped receptacle 47 disposed in the bore of an upright sleeve 48 integral with the cap 13. In this receptacle is disposed any suitable connection box 49 from which wires 50 may be led to a source of power. Surrounding the top of the box 49 and the receptacle 47 is a cup 51 of insulating material which can be slipped over these elements in a suitably tight manner.

In Fig. 7 is shown the casing 10 with the cap 13 and to the side walls of the casing is attached by any suitable means an overflow pipe 52 extending down to the drain outlet in the bottom of the basin in which the device is disposed. The top of the pipe 52 is disposed at a predetermined level so that there will be an overflow when the liquid in the tank or basin reaches a definite level. It is also seen that the bottom of the base plate 11 is provided with rubber suction disks 53 at spaced points to facilitate the firm adherence of the device within the basin or tub while in use.

In the operation of the device, it is observable that when the power is applied the motor will rotate and disks 24 will rotate the pins 23. As shown in Fig. 2, the left pin will press against the flange 22 and move the cap clock-wise until

the pin passes around and away from this portion of the flange. At the same time the other pin has been moving counter-clock-wise and will engage the other end of the flange as it reaches its furthest clock-wise swing and this engagement will then oscillate the flange back in a counter-clock-wise direction to its former position. Thus the cap and its attached paddles will be oscillated back and forth and effect the washing desired.

The auxiliary paddle blades 18 are shown to obtain a more thorough movement of the liquid when the dimensions of the tub or basin permit. It is seen that the device comprises four main separable parts. First the paddles can be easily removed from the cap; second the cap and the flange or driven element thereon can be lifted readily out of the casing; third the power unit comprising the motor, the gear train and the disks can be lifted right out of the casing when the cap is removed; and fourth the casing itself which can be firmly adhered to the bottom of the basin but as readily removed when desired. Thus all parts can be readily taken apart at any time with ease and dispatch for replacement, inspection, and repair as wished.

While my machine is waterproof and can be immersed without danger of leakage, an auxiliary shield member 55 is provided to extend over the belt pulley 31 and down to the base. By the same token, on the other side of the machine is furnished a shield member 56 to completely shield the motor in the event that any water should be splashed into the mechanism.

As shown in Figures 8 and 9 the casing 10 may be permanently welded or built into the sink unit 60, having a conventional dish sink 61 and a tub operation 62. In the particular housing shown there is provided between the tubs a rib 63 upon which the wringer can be mounted.

In all respects the operation of the machine is as heretofore described.

While the invention has been described in detail with respect to present preferred forms which it may assume, it is not to be limited to such details and forms since many changes and modifications may be made in the invention without departing from the spirit and scope of the invention in its broadest aspects. Hence, it is desired to cover any and all forms and modifications of the invention which may come within the language or scope of any one or more of the appended claims.

What I claim as my invention is:

1. In a device of the class described, a casing open at the top and closed at the bottom, an oscillatable flanged cap on top of the casing and fitted liquid-tight thereon, a dependent flange on the inside of the cap, a motor within the casing, a gear train operated by the motor, two disks driven by said train, eccentric pins on said disks to engage said flange alternately near the opposite ends thereof to oscillate the same.

2. In a device of the class described, a casing, a diametrical rib within on the floor of the casing, a motor within the casing, a plate supporting said motor and having a groove to receive said rib to position said plate within the casing, a gear train above and connected to said motor, a frame supporting said train, legs supporting said frame on said plate above said motor, disks above said train and driven thereby in opposite directions, eccentric pins on said disks, a flanged oscillatable cap disposed liquid-tight on said casing, and a dependent flange on said cap within

the casing alternately engaged by said pins to oscillate the cap on the casing.

3. In a device of the class described, a casing, a flanged cap thereon, a motor within the casing, an eccentric pin driven by the motor and disposed beneath the cap, a pivoted arm dependent from the cap to be engaged by said pin to oscillate said cap, and spring means backing said arm to resist thrust of the pin thereagainst.

4. In a device of the class described, a casing, a flanged cap thereon, a motor within the casing, two eccentric pins driven by the motor and disposed beneath the cap, pivoted arms dependent from the cap to be engaged respectively by said pins alternately to oscillate said cap on the casing, and a spring member backing said arms to resist the thrust of the pins thereagainst.

5. In a device of the class described, a casing, a diametrical rib within on the floor of the casing, a motor within the casing, a plate supporting said motor and having a groove to receive said rib to position said plate within the casing, a gear train above and connected to said motor, a frame supporting said train, legs supporting said frame on said plate above said motor, disks above said train and driven thereby in opposite directions, eccentric pins on said disks, a flanged oscillatable cap disposed liquid-tight on said casing, pivoted arms on the under side of said cap, spring means backing said arms, the pins alternately engaging said arms on opposite sides of the center of the cap to oscillate the same.

6. In a device of the class described, a casing, a liquid-tight oscillatable cap thereon, a motor within the casing, a gear train connected to and

10

15

20

25

30

35

operated by said motor, a pair of pivoted resiliently backed driven elements on said cap, two driving elements operated by the gear train to alternately engage said driven elements respectively to oscillate said cap.

7. In a device of the class described, a casing open at the top and closed at the bottom, a closed oscillatable flanged cap disposed in a liquid-tight manner on top of the casing, a motor within the casing, a gear train within the casing and operated by the motor, eccentric pins driven by the train, means on the lower face of the cap within the casing and dependent from the cap and engageable by said pins to oscillate said cap.

8. In a device of the class described, a casing, a closed oscillatable cap disposed over the top of the casing in a liquid-tight manner, a motor within the casing, a gear train within the casing and connected to and operated by said motor, a driven element on the lower face of the cap within the casing, and a driving element operated by the gear train and adapted to engage the driven element intermittently to oscillate the cap.
